(57) **CLAIM**

The ornamental design for an electrical box with quick-connect and release connection apertures, as shown and described.

DESCRIPTION

FIG. 1 is an exploded front perspective view of an electrical box with quick-connect and release connection apertures; FIG. 2 is a front view thereof; FIG. 3 is a rear view thereof; FIG. 4 is a left-hand side view thereof, wherein a right-hand side view is a mirror image of the left-hand side view; and, FIG. 5 is a top view thereof, wherein a bottom view is a mirror image of the top view.
